UNITED STATES PATENT OFFICE.

LUCJA OGRODNICZEK, OF SCRANTON, PENNSYLVANIA.

AVIATOR'S SAVER.

1,274,314.

Specification of Letters Patent. Patented July 30, 1918.

Application filed July 27, 1917. Serial No. 183,038.

To all whom it may concern:

Be it known that I, LUCJA OGRODNICZEK, a subject of Galicja Poland, residing at Scranton, in the county of Lackawanna, State of Pennsylvania, have invented certain new and useful Improvements in Aviators' Savers, of which the following is a specification.

This invention relates to certain new and useful improvements in saving the aviators in event of falling.

The primary object of the invention is that when put on before going up, in case of any event or injury of any kind to the aeroplane, while it is in the air the aviator drops down and through the "aviator's saver" is protected from death.

It will be understood that while the invention is primarily designed for aeroplanes it is also adaptable for balloons, etc.

With these general objects in view and others that will appear as the nature of the invention is better understood, the same consists in the novel construction, combination arrangement of parts hereinafter more fully described, illustrated in the accompanying drawings, and then claimed.

In the drawings forming a part of this application and in which like designating characters refer to corresponding parts throughout the several views:

Figure 1 is the completed "aviator's saver" in action, after the aviator has dropped from the aeroplane.

Fig. 2 presents the pilot, as he sits in the aeroplane, during flying, clad in the "aviator's saver."

Fig. 3 shows the leg, as it is fastened in the bottom part of the "aviator's saver."

Referring more in detail to the accompanying drawings the reference characters indicate parts as follows:

Fig. 1, A, upper umbrella, made in suitable pieces.

B, strings or cords leading and connecting A with C.

C, bodice, made to fit the aviator, which can be regulated with straps to the measure wanted.

D, lower umbrella, same as A but a bit

smaller connected with bodice C at the top and strings or cords E at the bottom.

E, strings or cords connecting lower umbrella D and foot rests F.

F, foot rests, connecting with strings E.

G, strap, binder fastened to the middle of the bodice, that is, with one end in the back and the other in the front, which comes between the legs of the aviator.

While the form of the invention herein shown and described is what is believed to be the preferred embodiment thereof, it is nevertheless to be understood that various forms, modifications and arrangements of the parts may be made without departing from the spirit and scope of the invention as claimed.

What I claim as new is:

1. A life saving garment for aviators, comprising a body band of a length extending from the chest down to the hips and open from top to bottom, means for fastening the band about the body, a pliant skirt like extension secured at its upper edge to the lower part of the band, a series of tension cords attached to the bottom of the extension and having ankle straps for attachment to the wearer's ankles, and tension cords attached to the upper part of the band and secured to a parachute.

2. A life saving garment for aviators, comprising a body band of a length extending from the chest down to the hips and open from top to bottom, means for fastening the band about the body, a pliant skirt like extension secured at its upper edge to the lower part of the band, a series of tension cords attached to the bottom of the extension and having ankle straps for attachment to the wearer's ankles, and tension cords attached to the upper part of the band and secured to a parachute, the latter adapted to be folded down back of the wearer so as to be out of the way when the device is worn.

In testimony whereof I affix my signature.

LUCJA OGRODNICZEK.
